SPRING DEVICE

Glen E. Mather and Donald C. Green, Logansport, Ind., assignors to Rockwell-Standard Corporation, a corporation of Pennsylvania

Application May 3, 1955, Serial No. 505,582

24 Claims. (Cl. 267—44)

This invention relates to a spring device effective as a highly elastic leaf or beam in supporting a load, and more particularly, relates to an adjustable leaf load spring whose beam depth in cross section can be varied while the spring is supporting the load to stiffen the same against excessive deflection under load. An illustrative embodiment of the invention is shown in the accompanying drawings in which:

Figures 1 and 2 are top plan and side elevational views of the tension member of the spring device;

Figure 3 is a fragmentary end section of the complete spring device;

Figure 4 is a transverse section taken along the lines IV—IV of Figure 3;

Figure 5 is a sectional view similar to Figure 4 but showing the spring device inflated;

Figure 6 is a view similar to Figure 4 but showing a modified form of the fabricated spring; and

Figure 7 is a perspective view, partially diagrammatic, of the spring device applied in perspective to a vehicle suspension.

In more specific reference to Figures 1—5 and 7 of the drawings, a fabricated flat longitudinal leaf spring 10 is shown having an upper tension strip or leaf 11 and a lower compression strip or leaf 12 which are spaced apart vertically from one another so as to define a shallow, longitudinally extending, included chamber 15 forming the hollow interior of the spring device 10. The spring device 10 has its opposite end portions turned to form a pair of bent integral spring eyes 13 and the spring device has a camber or curve of conventional shape in its body portion.

The long edges of the compression leaf 12 are bent upwardly to form flanges 12a so as to present a shallow channel cross section, and the flanges are seam welded at 14 to the opposite sides of the tension leaf 11 and the opposite extremities of the leaf 12 are similarly welded at 14 to the underside of the tension leaf 11. Accordingly, the chamber 15 within the hollow interior of the fabricated spring device 10 has a continuous line of welding at the seams and forms a fluid-tight chamber. Adjacent one of the eyes 13, a vertically disposed opening 16 is formed in the tension leaf 11 to communicate with the hollow interior 15 of the spring device when the compression leaf 12 is welded into place therebelow. A hose receiving fitting 17 is secured to the leaf 11 about the mouth of the opening 16, being welded thereto at 18 to form a fluid-tight joint for charging and relieving the pressure therein.

The following is given as an example of the dimensions of the upper tension leaf 11 which is preferably strip steel:

Length ----- 48"
Width ----- 6"
Thickness ----- 0.375" 70

2

sions of the lower compression leaf 12 which is preferably strip steel:

Length ----- 46"
Width of channel ----- 6"
Thickness ----- 0.125"

From the foregoing dimensions, it is apparent that the lower compression leaf 12 is only approximately one-third as thick as the upper tension leaf 11, and it is further apparent that the width to thickness ratio (48:1) of the springy lower leaf is proportioned such that the leaf is flexible transversely and can crown or bulge between its opposite long edges in a direction of bow at right angles to the lengthwise bow or camber of the spring device 10 between its opposite ends.

Internal inflation of the chamber 15 in the spring device 10 produces such a crowning or bulging action of the lower leaf 12 according to Figure 5. This action obviously increases the beam depth of the spring device 10 rendering the calculated moment of inertia of the cross section considerably greater and greatly improving the beam stiffness of the spring device 10 regardless of its application as either a semielliptic spring, a cantilever spring, or otherwise.

In Figure 6, a modified showing 10a of the spring device of the foregoing figures is illustrated. The modified spring device 10a is a flat, one-piece member formed of seamless steel tubing thicker at one side than the other such that the upper, relatively thick tension leaf and the relatively thinner compression leaf portions 19 jointly define an included inflatable chamber 15 substantially identical in appearance to the inflatable chamber of the spring device 10 of the preceding figures. Internal inflation of the spring device 10a of Figure 6 results in an improved and deepened beam section the same as shown in Figure 5.

In Figure 7, the composite spring device 10 is shown embodied in a semielliptic, longitudinal leaf spring suspension for a load carrying supported structure comprising a longitudinally extending vehicle side rail 20 of general U-shaped channel section and being inwardly open with respect to an opposite side rail (not shown). A similar spring device 10 may be provided for the opposite side rail. The illustrated side rail 20 at its rear end has a bracket 22 mounted to the inside of the lower one of the opposed legs of the U-shaped channel. The bracket 22 fixedly carries a pivot pin 24 swingably supporting a depending double-link shackle 26 which carries another pivot pin 28 at its lower swinging end. The pivot pin 28 is received in the eye 13 at the rear end of the composite spring device 10. In the front eye 13 at the opposite end of the spring device 10, another pivot pin 30 is received which is carried by a depending pair of apertured spaced apart ears on a bracket 32 mounted to the underside of the side rail 20.

Between its opposite end portions, the spring device 10 carries a steel pillow block 34 which supports a hollow axle housing 36. The axle housing 36 receives a longitudinally extending drive axle 38 journaled therein and at its outer end, the housing 36 carries a brake backing plate 40 for the brake of a wheel (not shown) driven by the axle 38. A frustum-shaped rubber jounce bumper member 41 is mounted to the underside of the side rail 20 in a position of vertical alignment above the axle housing 36 so as to engage a bumper plate 42 which is rigidly carried by the housing 36 and which moves conjointly in the path of motion therewith. A powerful permanent magnet 44 is also carried by the bumper plate 42 at a position offset from the latter's point of engagement with the bumper 41. A pair of threaded U-bolts 46 is provided which encircle the upper surface of the bumper plate 42 and hang downwardly below the axle

The following is given as an example of the dimen-

housing 36. The threaded end portions of the U-bolts 46 are passed through a retainer plate 48 on the underside of the spring 10 and are secured thereto as by means of a set of nuts threadably received on the ends of the U-bolts.

The fitting 17 at the forward end of the spring device 10 is a bidirectional inflating fitting through which pressure fluid, preferably light oil or other readily circulatable hydraulic fluid or non-viscous liquid is automatically communicated into and out of the hollow interior thereof and the fitting 17 receives the moving end of a flexible rubber hose connector 50 which is secured fast at its opposite end to a stationary fitting 52 mounted within the channel of the vehicle side rail 20. The fitting 52 is hollow for communicating pressure fluid to the connector 50 and is supplied with pressure fluid by means of a conduit 54 secured at its opposite end to a T-fitting 56 located in an electronic-hydraulic control component 57 which may be securely mounted to the frame structure supported by the frame side rail 20. A rotary fluid pump 58 included in the control component 57 has a pair of inner and outer lobed rotors which differ by one in the number of lobes thereon and which are arranged for rotation such that the included chambers 60 therebetween trap pressure fluid to conduct it in quantities by positive displacement from a pump intake supply conduit 62 into a pressurized discharge conduit 64 connected to the T-fitting 56. Interposed in the discharge conduit 64, a pressure blow-off valve fitting is provided at 66 for by-passing fluid above a predetermined pressure back into the intake conduit 62. The pump intake supply conduit 62 draws suction from a reservoir tank 68 containing a supply of pressure fluid at atmospheric pressure.

Another pump by-pass fitting in the form of a valve casing 70 is connected between one leg of the T-fitting 56 and the pump intake supply conduit 62. The valve casing 70 includes a port therein controlled by means of a needle valve 72. A valve positioning electric motor 74 drives the needle valve into its appropriate adjusted positions for regulating the fluid pressure by means of an interposed pinion and rack connection at 76. The motor 74 is energized and reversibly controlled in its actuation by means of a combined amplifier and motor control device diagrammatically indicated at 78. The amplification portion of the device 78 actuates the motor control portion so as to keep the regulating valve adjusted in response to electrically generated signals received through a cable 80, the cable 80 being connected to a stationary sensing unit 82 disposed vertically above the movable axle supported permanent magnet 44. The sensing unit 82 may include an induction coil pickup element 83 therewithin which is effective to register and transmit an electromagnetically induced voltage from the magnet 44 and communicate the same to the amplifier and motor control device 78. A pair of gusset plates 86 welded to the frame side rail 20 carries a mounting bracket 84 which supports the sensing unit 82 in a fixed position above the magnet 44.

Under increasing load on the load carrying supported part and the side rail 20, the spring device 10 deflects so as to bring the permanent magnet unit 44 into closer proximity to the sensing unit 82. The changing electromagnetic field linking the two units 44 and 82 thus becomes relatively stronger in its action on the sensing unit and on the amplifier device 78 when the distance between the units 44 and 82 is materially diminished, or conversely, that field weakens when the parts occupy widely spaced positions and produces only feeble signals to be fed to the amplifier device.

In operation, any change causing the suspension parts 44 and 82 to move into and take working positions which are either widely spaced apart or spaced materially closer together is sensed by the device 78 which in turn causes selective directional rotation of the motor 74. For example, when parts 44 and 82 move apart, device 78 con-

trols directional rotation of motor 74 to move the needle valve 72 away from its seat and when parts 44 and 82 move toward each other, device 78 controls directional rotation of motor 74 so as to move the needle valve 72 toward the valve seat. The rotary pump 58 continually circulates fluid through the path including the bypass valve casing 70 and, as the needle valve 72 is adjusted in a direction toward its seat in the by-pass, pump pressure builds up the back pressure within the hollow interior of the fluid-tight spring device 10.

This constantly by-passing system of circulation through the valve casing 70 with the needle in its adjusted positions enables a precise degree of fluid pressure regulation controlled automatically in dependence upon the axle-connected and frame-member-connected parts 44 and 82 which, as these members reciprocate, cooperate to regulate that pressure as an inverse function of the distance between the members. Changes in the regulated pressure directly adjust the internal back pressure or inflation pressure of the spring chamber 15 which accommodates thereto through the bi-directional fitting 17 which, as noted, is the common communication functioning both to charge and to relieve inflation pressure as appropriate in the former.

Under inflation pressure, the compression leaf 12 bulges or crowns throughout the greater part of the length of the spring device 10 so as to increase its beam depth and materially increase the stiffness and resistance thereof to deflection. Accordingly, the spring 10 resists being forced toward the side rail 20 in direct proportion to its closeness thereto and, when inflated, tends to separate therefrom. In case two transversely aligned spring devices 10 are located on opposite sides of a vehicle body, the spring devices will automatically tend to provide an anti-roll stability to the vehicle inasmuch as body roll to either side is naturally attended by an approaching of the load carrying side rail and the spring suspension toward one another. A stiffening resistance to roll, therefore, results and the suspension under its internal pressurization tends to lift the side rail thereabove rather than collapse and allow the same to lower.

As herein disclosed, the adjustably stiffenable spring invention is shown embodied in a vehicle spring suspension. It is evident that the stiffening spring feature has application to other spring suspensions embodied in load carrying structures of any description in which the load is subject to variance.

While we have described certain presently preferred embodiments of our invention, it is to be understood that it may be otherwise embodied within the scope of the appended claims.

We claim:

1. A load carrying supported part, a leaf type load spring part therefor having an elongated flexible wall portion forming one side of a longitudinally extending, inflatable chamber within the leaf of the load spring part, flexible connector means disposed between and secured at its opposite ends to the parts for introducing pressure fluid into the inflatable chamber to bulge said flexible wall portion and increase the beam depth of the load spring part for increasing the stiffness thereof, and means providing a fluid pressure system coupled to said connector means.

2. A fluid inflatable spring member formed with a longitudinally extending hollow interior and having tension and compression leaves forming the respective walls at the opposite sides of the hollow interior thereof, said compression leaf being relatively thin and the tension leaf being at least approximately three times thicker, and bidirectional fluid fitting means communicatively connected to the interior of the leaf spring member to charge and relieve the inflation pressure thereof so as to selectively bulge the thin wall and thereby apply ten-

sion strain substantially exclusively on the leaf already under compression.

3. A fluid inflatable spring member formed with a longitudinally extending hollow interior and having a bulging compression wall on one side thereof, having a stiff, thicker tension wall at the opposite side which integrally carries a spring eye at each of its ends, and having a bidirectional fluid fitting means mounted to the tension wall and connected to the interior of the spring member to charge and relieve the inflation pressure thereof so as to bulge the thinner wall and thus apply tension strains to the compression wall instead of applying further tension strains to the already tensioned thicker wall.

4. In combination, first and second relatively reciprocable suspension parts, said first part comprising an internally inflatable leaf spring part having a bulgable wall portion and a fluid-tight interior, a source of regulated inflating fluid connected to the interior of the leaf spring part, and means for automatically regulating the pressure of the inflating fluid in accordance with the distance between the parts as they reciprocate.

5. In combination, first and second relatively reciprocable suspension members, said first member comprising an internally inflatable leaf spring member having a bulgable wall portion and a fluid-tight interior, a flexible hose having one end structurally fast to said second member and having the opposite end fast to and connected to the interior of the first member, and fluid pressure regulating means communicatively connected to said one end of the flexible hose to apply and to automatically regulate the magnitude of the inflating pressure applied to the spring through the hose in proportion to the direct proximity of the members to one another.

6. In combination, first and second relatively reciprocable suspension parts at least one of which elastically deflects during relative reciprocation and stiffens when it swells under pressure, said first part having magnet means mounted thereon which confronts the second part and which directs theretoward a magnetic field which varies in its effect as a function of the distance or proximity between parts, fluid means connected to pressurize and stiffen said one part, and means on the second part sensitive to the effectiveness of the magnetic field for controlling the fluid means and causing a stiffening of the said one part against deflection as a function of the proximity of the parts.

7. In a suspension, first and second relatively reciprocable parts, at least one of which elastically flexes between its ends during relative reciprocation and which, when straightened, is caused to separate from the other part, said first part having magnet means mounted thereon which confronts the second part and which directs theretoward a magnetic field which varies in its effect as a function of the proximity between parts, fluid means connected to pressurize and stiffen said one part, and actuating means sensitive to the effectiveness of the magnetic field for controlling the fluid means and causing said one part to straighten and separate from an attained position thereof of near proximity with respect to the other part.

8. In combination, first and second relatively reciprocable suspension members, said first member comprising an internally inflatable spring member having wall portions of different gauges on opposite sides of a fluid-tight interior of noncircular cross section, a source of normally by-passed circulating liquid connected to the interior of the first member, and fluid pressure regulating means including a valve portion for blocking said by-pass to immediately increase the liquid back pressure in the interior of the first member for bulging the thinner gauge wall portion.

9. In combination, first and second relatively reciprocable suspension members, said first member comprising a generally flat liquid-filled spring member having vertically spaced flat sides of differing gauges on opposite

sides of a fluid-tight interior, a source of normally bypassed circulating liquid having means connecting it to the liquid inside the first member comprising a fitting connected to said first member at the top of the upper side thereof, and fluid pressure regulating means including a valve portion for blocking said by-pass to immediately increase the liquid back pressure inside the first member for bulging the side having the thinner gauge.

10. In combination, first and second relatively reciprocable suspension members, said first member comprising a liquid-filled hollow spring member having vertically spaced longitudinal walls of differing gauges, the thicker gauge wall being on the upper side and the thinner gauge wall being on the lower side of the fluid-tight hollow interior of the first member, a source of normally bypassed circulating liquid having means connecting it to the liquid inside the first member comprising a fitting connected to a relatively static portion of said first member at the top of the upper wall thereof for hydraulically internally bulging the opposite wall of thinner gauge thereby to provide the section modulus of said first member with a changed moment of inertia.

11. In a vehicle, a chassis, an axle assembly, and a leaf spring suspension between said chassis and axle assembly comprising a longitudinally extending leaf member having a longitudinally extending internal fluid pressure chamber with a flexible wall, means providing a source of fluid pressure and connecting it to said chamber, and means responsive to changes in distance between said axle assembly and chassis as permitted by said spring suspension for automatically regulating said pressure in said chamber.

12. In the vehicle defined in claim 11, said last-named means being effective to increase the pressure in said chamber to increase the effective beam cross section of said leaf member and thereby stiffen it as said distance decreases.

13. In the vehicle defined in claim 11, a pump for developing said fluid pressure, and said last-named means comprising automatic valving means connected to the pump outlet.

14. In the vehicle defined in claim 13, a supply conduit between the pump and said chamber, a bypass conduit for said pump connected to said supply conduit, and said valving means being provided in said bypass conduit.

15. A leaf spring assembly comprising substantially laterally and longitudinally coextensive transversely flexible elongate metal members rigidly secured together along their lateral edges so as to form a fluid tight longitudinally extending fluid pressure chamber therebetween, and a fluid pressure inlet to said chamber, one of said members being sufficiently thinner than the other member as to flex to increase the beam cross section of said assembly in controlled response to introduction of fluid under pressure into said chamber.

16. The leaf spring assembly defined in claim 15, wherein said other member is a laterally inflexible spring leaf, and said one member is welded peripherally to said other member.

17. The leaf spring assembly defined in claim 15, wherein said members are integrally joined.

18. The leaf spring assembly defined in claim 15, wherein said other member is at least three times as thick as said one member.

19. In a vehicle having a chassis and at least one transverse axle assembly connected thereto by a leaf spring suspension assembly that is operatively connected to the chassis and said axle assembly, said leaf spring assembly being formed with an internal longitudinally extending fluid pressure chamber having an inlet for introducing fluid under pressure and a flexible wall, a controllable source of fluid pressure connected to said inlet, and means including cooperating means relatively movable with the axle assembly and chassis for automatically controlling the degree of fluid pressure within said chamber.

ber to change the beam cross section of said leaf spring assembly in response to changes in relative vertical positions of said axle assembly and chassis.

20. In the vehicle defined in claim 19, said leaf spring assembly being pivotally attached at opposite ends to said chassis and intermediately attached to said axle assembly.

21. In the vehicle defined in claim 19, said last-named means comprising relatively movable means providing a magnetic field and a sensing device adapted to relatively move in said field in response to said positional changes of the chassis and axle assembly, and means actuated by said sensing means for varying said fluid pressure.

22. In the vehicle defined in claim 21, a pump for developing said source of fluid pressure, and said last-named means comprising a bypass for the pump outlet, a valve in said bypass, and an electric motor controlled by said sensing means for adjusting said valve to vary the outlet fluid pressure of said pump.

23. In a vehicle assembly, a chassis, an axle assembly, a leaf spring assembly extending longitudinally of the vehicle to flexibly suspend said chassis on said axle assembly, said leaf spring assembly comprising at least one elongated spring leaf containing a longitudinally extending internal chamber having a flexible wall, and means for automatically varying the spring rate in response to relative positional changes of the axle assembly and chassis comprising means actuated in response to said changes for varying the fluid pressure in said chamber to thereby vary the spring leaf cross section.

24. In a suspension; first and second relatively movable members; said first member comprising an inflatable leaf spring having a bulgeable wall portion and a fluid-tight interior; a source of regulated inflating fluid connected to the interior of said spring; fluid pressure regulating means; and means, effective as the members move relatively to each other to operate said regulating means to regulate the pressure of the inflating fluid as an inverse function of the distance between the members, comprising cooperating means connected to each of said members, relatively movable with said members and providing a linking magnetic field, and means for sensing said linking magnetic field operably connected to said pressure regulating means.
